his Attorney:

UNITED STATES PATENT OFFICE.

ROBERT WILLIAMS, OF ST. LOUIS, MISSOURI, ASSIGNOR OF ONE-FOURTH TO CHARLES MATHEIS, OF ST. LOUIS, MISSOURI.

TROLLEY-HARP.

1,221,257.

Specification of Letters Patent.

Patented Apr. 3, 1917.

Application filed November 6, 1916. Serial No. 129,863.

To all whom it may concern:

Be it known that I, ROBERT WILLIAMS, a citizen of the United States, and residing at the city of St. Louis, State of Missouri, have invented a certain new and useful Improvement in Trolley-Harps, of which the following is a specification, reference being had to the accompanying drawing, forming a part thereof.

10 This invention relates to a certain new and useful improvement in trolley-harps. The principal object of my present invention is to provide a comparatively simple and inexpensive trolley-harp in which the 15 usual trolley-wheel supporting-member or bearing is yieldable, relatively to the usual trolley pole, both vertically and pivotally, so as to compensate for elevations and depressions in the usual trolley-wire and also to 20 obviate jumping of the trolley-wire by the trolley-wheel especially in rounding corners, bends, or the like in the wire.

With the above and other objects in view, my present invention resides in certain 25 novel features of form, construction, arrangement, and combination of parts, all as will hereinafter be described and afterward pointed out in the claims.

In the accompanying drawing, which illustrates my invention in preferred form,

Figure 1 is a plan view of a trolley-harp embodying my invention, the trolley-harp being shown with its wheel in operative engagement with a trolley-wire;

35 Fig. 2 is a side elevational view of the trolley-harp with its wheel similarly in engagement with the trolley-wire;

Fig. 3 is an end view of the same;

Fig. 4 is also a side elevational view of 40 the trolley-harp and its wheel, the trolley-wire being omitted; and

Fig. 5 is a sectional view on approximately the line 5—5, Fig. 2.

Referring to the said drawing, in which 45 like reference characters refer to like parts throughout the several views, 1 indicates the main plate of the harp, plate 1 being of metallic material of suitable rigidity and preferably rectangular in outline, as seen in 50 Fig. 5. Projecting obliquely downwardly from one end of plate 1, is a preferably integral socket-extension 2 in which the upper end of the trolley-pole 3 is adapted to seat,

fastening-devices 4 engaging both socket-extension 2 and pole 3 to secure the same 55 together. The pole 3 may be mounted upon the car (not shown) in any suitable or desirable manner, the plate 1 extending in a plane approximately horizontally disposed to the roof of the car when the pole 3 is in 60 its usual obliquely-disposed operative or normal position.

Within its area, plate 1 is cut-away or perforated to provide a pair of spaced apart preferably square apertures 5—5, in which 65 apertures slidably fit likewise preferably square posts 6—6 fixed at their upper end to, and depending from, a second or upper plate 7 flatwise disposed relatively to main plate 1.

70 Intermediate apertures 5—5, main plate 1 is further perforated to provide a central preferably circular aperture 8, in which aperture 8 similarly slidably fits a cylindrical post 9 also fixed at or adjacent its upper 75 end to, and depending from, second or upper plate 7. Threaded and secured upon the lower ends of posts 6—6 and 9 are nuts or the like 10 adapted to loosely secure plates 1 and 7 together, a spring 11 coiled on central post 9 and interposed between plates 1 and 7 yieldingly maintaining the plates 1 and 7 in suitably spaced apart relation.

Projecting upwardly from the upper end of central post 9 or otherwise fixed upon the 85 upper face of plate 7, is an enlargement or bearing 12, pivotally mounted upon which is the trolley-supporting-member proper 13. This member 13 is formed preferably from a single strip of suitable metallic material, the strip being first bent to provide the base-portion or wall 14 and then doubled upon itself, as at 15—15, to reinforce or strengthen the base-portion or wall 14 at its ends, the ends of the strip being then bent to provide the upwardly disposed legs 16—16. Journaled to rotate between the legs 16—16, is a suitable grooved trolley-wheel 17.

Attached at one end to preferably the rear 100 end of upper plate 7, as seen particularly in Fig. 1, and at their other end to the projecting ends 15 of wall 14 of the trolley-wheel supporting-member 13, are oppositely disposed somewhat obliquely extending 105 coiled springs or the like 18 adapted to

yieldingly hold the trolley-wheel member 13 in normal position with its wall or base-portion 14 transversely disposed at approximately right angles to the plates 1 and 7.

- 5 Due to the spring 11, which is somewhat compressed when the trolley-wheel 17 is in engagement with the usual trolley-wire 19, the trolley-wheel supporting-member 13 and its wheel 17, in use or operation, will freely 10 yield vertically to compensate for elevations or depressions in the trolley-wire. Thus the tension of the trolley-wheel 17 on the wire 19 is approximately uniform and steady, and 15 wear and tear on both the trolley-wheel and wire, as well as arcing therebetween and the consequent damaging effects thereof, are largely avoided. Further, in the travel of the car, one or the other of the springs 18, as the case may be, will first readily yield to 20 permit the member 13 and its wheel 17 to pivotally move to the right or left, as in rounding a corner or the like, so that the wheel 17 may freely follow the wire without jumping and without unnecessary wear, 25 the said spring afterward returning the member 13 and its wheel 17 to normal position.

Suitably attached preferably to plate 1, is a rope or the like 20, whereby the pole 3 30 and its harp may be conveniently manipulated, as is usual, into or out of engagement with the trolley-wire.

The parts of my new harp being, as stated, 35 of suitable metallic material, the current from the wire 19 will freely flow there- 40 through to the pole 3 and its electrical connections, as will be well understood.

I am aware that minor changes in the 45 form, construction, arrangement, and combination of the several parts of my new trolley-harp, may be made and substituted for those herein shown and described without departing from the nature and principle of my invention.

Having thus described my invention, what

I claim and desire to secure by Letters Patent is:

1. In a trolley-harp, a pair of superposed plates, the lower plate being provided transversely with a plurality of apertures, posts 50 depending from the upper plate, said posts slidably fitting in the apertures of the lower plate, means on said posts beneath the lower plate for loosely securing said plates together, a spring interposed between said plates for yieldingly maintaining the same in spaced relation, said spring being coiled on one of the posts, a trolley-wheel supporting-member pivoted for rotation upon the upper plate, and springs positioned above 60 the upper plate and engaging the upper plate and said supporting-member for yieldingly holding the supporting-member in normal position relatively to both the plates. 55

2. In a trolley-harp, a pair of superposed 65 plates, the lower plate being provided transversely with a plurality of apertures, a socket-extension on the lower plate, said extension being adapted for engagement with a trolley-pole, posts depending from the 70 upper plate, said posts slidably fitting in the apertures of the lower plate, nuts threaded on said posts beneath the lower plate for loosely securing the plates together, a coiled 75 spring interposed between the plates for yieldingly maintaining the plates in spaced relation, said spring being coiled on one of the posts, a trolley-wheel supporting-member pivoted for rotary movement upon the upper plate, said supporting-member comprising a base-wall reinforced at its ends, and diverging coiled springs positioned 80 above the upper plate and engaging the upper plate and the reinforced ends of the supporting-member for yieldingly holding the 85 supporting-member in normal position relatively to both the plates.

In testimony whereof, I have signed my name to this specification.

ROBERT WILLIAMS.
